Patented Oct. 7, 1919.

UNITED STATES PATENT OFFICE.

ROLAND H. CLARK, OF ZANONI, VIRGINIA.

FLYING-TARGET.

1,317,958.

Specification of Letters Patent.

Patented Oct. 7, 1919.

Application filed March 8, 1919. Serial No. 281,385.

To all whom it may concern:

Be it known that I, ROLAND H. CLARK, a citizen of the United States, and a resident of Zanoni, in the county of Gloucester and

5 State of Virginia, have invented certain new and useful Improvements in Flying-Targets, of which the following is a specification, reference being made to the accompanying drawings, forming a part thereof.

10 My invention relates to improvements in flying targets which are adapted to be thrown into the air by any suitable spring-trap mechanism, such targets to be shot at during their flight to test marksmanship,

15 and the objects of my invention are, among other things, to provide a suitable flying target which shall closely resemble a live bird in flight, which target will be made or formed of easily friable material and will

20 have wings and tail feathers adapted to balance the weight of the target during its flight, as well as to approximate the form and appearance of a live bird. My device also provides an inexpensive imitation of a

25 live bird which, when propelled into flight by mechanical means, will readily soar upward from the line of projection, without endangering its fragile structure due to the impact of propulsion when thrown into the

30 air by any suitable means.

With these and other objects in view, my invention comprises the various structural features hereinafter fully described and pointed out in the claims. A preferred embodiment of my invention is shown in the accompanying drawings in which—

Figure is a perspective view of the target in the course of its flight;

Fig. 2 is an enlarged central longitudinal 40 section of the target shown in Fig. 1;

Fig. 3 is a central longitudinal section of a modified form of my target;

Fig. 4 is a transverse section taken on the line 4—4 of Fig. 2 looking in the direction 45 of the arrow.

Similar numerals refer to similar parts throughout the several figures.

Referring to the drawings, the body 6 of the target is made in close resemblance to the form and contour of the body and head of a live bird, the body 6 being composed of the usual tar and clay composition, suitably baked, such as is commonly employed in the manufacture of inverted saucer-shaped "clay pigeons". Such fragile material forms a thin contour for the bird, and is easily

broken when hit by shot; this friable body may be made in any suitable manner to produce the requisite bird-like form. Midway in the body are two oppositely disposed 60 longitudinal slots 7 and 8 through which is passed transversely an oblong strip 9 made of stiff paper or card-board with the front corners rounded to form the outstretched wings 10 and 11, as shown in Figs. 1 and 4. 65 The slots 7 and 8 are slightly inclined upwardly toward the head of the body 6 as shown in Figs. 2 and 3, and the wing strip 9 is frictionally held midway in the slots 7 and 8 so as to form the two outstretched 70 wings 10 and 11 as shown. Near the tail end of the body 6 I preferably form two holes 12 and 13 on either side of the body in which the quill tail feathers 14 and 15 respectively are secured. These tail feathers 75 14 and 15 tend to assist in guiding and steadyng the target in flight, and in Figs. 2 and 3 I have shown another hole 16 at the top of the extreme tail portion of the body 6 in which other feathers (not shown) may 80 be inserted if found necessary or desirable to guide or steady my improved target in flight.

In Fig. 3 I have shown a modified form for the body 6 in which a centrally disposed hole 17 is formed in the breast portion of the body 6 and a similarly sized hole 18 is also made through the tail end to which a yielding washer 19 made of felt or cork is affixed as shown. These holes 17 and 90 18 are preferably formed along the major longitudinal axis of the body 6. This form is devised to be used with a trap in which the body 6 is slidably mounted upon a rod projecting from the spring mechanism (not 95 shown), which rod extends through the two holes 17 and 18, the rod serving to support and then give the proper line of projection for the target's flight. The yielding washer 19 acts as a buffer between the friable body 100 6 and the cross-bar of the trap so as to prevent the body 6 from being broken or cracked at the instant of propulsion from the trap.

Any suitable mechanism for projecting 105 my target into flight may be used, the construction shown in Fig. 2 being adapted to lie in a basket or cradle mounted on the trap end which cradle is projected outwardly with sufficient velocity to give the necessary 110 impulse to the body 6 to cause the latter to be carried upwardly in flight by means of

the upwardly inclined wings 10 and 11. The inclination to these wings enables the target to lift somewhat from the line of its projection after the manner of the rising 5 of game-birds when flushed. When the shot from the gun strikes the body 6 it immediately breaks and falls after the manner of "clay pigeons" now in use.

From the foregoing it is obvious that I 10 have provided a flying target having many advantages in flight and in the attractive appearance of its bird-like form, wholly unattainable by the customary "clay pigeons"; and further that such targets may be readily 15 manufactured to embody such increased benefits to test marksmanship. Many slight changes may be made in the form of the several parts embodied in my target without departing from the principle and scope 20 of my invention.

I claim as my invention:—

1. A flying target comprising a body shaped to resemble the contour of a bird and formed of friable material, such body 25 having outstretched flat wings secured to the body, said wings being upwardly inclined toward the head of the body.
2. A flying target comprising a body shaped to resemble the contour of a bird 30 and formed of friable material, such body having outstretched flat wings secured to the upper portion of the body, said wings being upwardly inclined toward the head of the body.
3. A flying target comprising a body 35 shaped to resemble the contour of a bird and formed of friable material, such body having outstretched flat wings secured to the upper portion of the body, said wings 40 being upwardly inclined toward the head of the body and having their front corners rounded.
4. A flying target comprising a body shaped to resemble the contour of a bird 45 and formed of friable material, said body having outstretched flat wings secured to the body, said wings being upwardly inclined toward the head of the body, and tail feathers secured to the sides and top of the 50 tail end of the body.
5. A flying target comprising a body shaped to resemble the contour of a bird and formed of friable material, upwardly 55 inclined oppositely disposed longitudinal slots formed in the bird body, an oblong

strip of stiff material passing through said slots and frictionally held midway therein to form outstretched wings.

6. A flying target comprising a body shaped to resemble the contour of a bird 60 and formed of friable material, upwardly inclined oppositely disposed longitudinal slots formed in the bird body, an oblong flat strip of stiff material passing through said slots and frictionally held midway 65 therein to form outstretched wings the front edges of the wing strip being rounded.

7. A flying target comprising a body shaped to resemble the contour of a bird 70 and formed of friable material, said body having outstretched flat wings secured to the body, said wings being upwardly inclined toward the head of the body, two holes formed in said body along its major longitudinal axis, and yielding means affixed 75 to the tail end of the body about one of said holes.

8. A flying target comprising a body shaped to resemble the contour of a bird and formed of friable material, upwardly 80 inclined oppositely disposed longitudinal slots formed in the bird body, an oblong strip of stiff material passing through said slots and frictionally held midway therein to form outstretched wings, two holes 85 formed in said body along its major longitudinal axis, and a yielding washer affixed on the tail end of the body around one of said holes.

9. A flying target comprising a hollow 90 body shaped to resemble the contour of a bird and formed of friable material, oppositely disposed longitudinal slots formed in the bird body, and a strip of stiff material passing through said slots and secured substantially midway therein to form outstretched wings.

10. A flying target comprising a body shaped to resemble the contour of a bird and formed of friable material, upwardly 100 inclined oppositely disposed longitudinal slots formed in the bird body, an oblong flat strip of stiff material passing through said slots and frictionally held midway therein to form outstretched wings, two holes 105 formed in said body beneath said slots along its major longitudinal axis, and a yielding washer affixed on the tail end of the body around one of said holes.

ROLAND H. CLARK.
